UNITED STATES PATENT OFFICE.

ERNEST KLEIN, OF NEW YORK, N. Y.

GROUND-CONNECTOR.

1,095,732

Specification of Letters Patent.

Patented May 5, 1914.

Application filed April 28, 1913. Serial No. 763,981.

To all whom it may concern:

Be it known that I, ERNEST KLEIN, a citizen of the United States, and a resident of the borough of Manhattan, county, city, 5 and State of New York, have invented certain new and useful Improvements in Ground-Connectors, set forth in the following specification.

This invention relates to ground connectors of the type clamped to embrace a pipe or equivalent ground conductor and make a good electrical connection therewith.

The objects of the invention are to provide an inexpensive practical connector 15 which shall be indeterminably adjustable as to the size of pipe for which it is adapted; one in which comparatively thin sheet metal may be employed with safety so far as secure clamping and good electrical connecting 20 are concerned; and one in which the nut of the clamping bolt is locked against turning.

The above and more detailed features of the invention will be clear from the illustrative embodiments described and claimed 25 below in connection with the accompanying drawings, which form a part of this application, in which like characters refer to corresponding parts, and in which,—

Figure 1 is a view cross-wise of the ground pipe showing the connector partly in section, and partly in elevation; Fig. 2 is a top plan of the connector; Fig. 3 is a detail section through the head; Fig. 4 is a 35 plan of the head; Fig. 5 shows a modification for the free end of the flexible band; and Fig. 6 shows a bottom plan of the so modified band.

A single stamping of sheet metal such as 40 hard drawn copper is stamped at one end to form a suitable wire terminal 1 which may be tinned, to facilitate soldering a terminal conductor. The flat body portion 13 is centrally perforated to pass the shank of the 45 bolt or screw 2 and is integral with the curved head H which is enlarged laterally to accommodate the laterally extending slots 3 and 4 demarking the sheet-metal gripping bar 5. The slots 3 and 4 pass the flexible 50 adjustable band 6 of thin sheet metal, the end of which first enters slots 3 and passes out slot 4 so that the band 6 overlies the head H and passes under the bar 5 or in other words is woven through the slots. The 55 metal facing the bar 5 along the edge of slot 3 may be crimped up to form the gripping

jaw 8 and the metal along the opposite edge of the bar adjacent the slot 4 may be crimped down to form the gripping jaw 9. Back over this jaw 9 the end 7 of the band 6 is 60 adapted to be bent into the kink 10 flat against the bar 5. The free end of the band 6 is perforated to pass the shank of the bolt 2 and may be doubled back on itself to form the ledge 11 for the engagement of the nut 65 12 or this free end may be wrapped about the nut 12 as shown in Figs. 5 and 6, the wrappings 13, 14 and 15 being perforated to pass the shank 2. These wrappings about the nut 12 prevent its turning even when the 70 band 6 is of very thin metal and cause the stress from the bolt 2 on the nut 12 to be transmitted from the side face of the nut 12 against the width of the free end of the metal band 6, which is wrapped upon the 75 nut 12. The nut may be permanently assembled by denting down the lips 16 and 17.

P indicates the ground pipe or other ground conductor to be gripped. The ground connector normally assembled as 80 shown in Fig. 1 may be applied to the pipe P by unscrewing the bolt 2; clasping the band 6 about the pipe; and reengaging the bolt 2 with its nut 12. The end 7 of the band 6 should then be drawn forward to 85 take up all slack and then be kinked back over the bar 5. Any surplus may then be snipped off. All the slack about the pipe P may be taken up by manually pulling the band 6 through the slots 3 and 4, so that 90 this band is adapted to be gripped in any indeterminate part of its length as distinguished from being gripped in fixed spaced steps such as might be formed by cut-out portions in the band adapted to be engaged 95 by an inserted part. When the parts are thus embracing the pipe P, the jaw 8 at the edge of the slot 3 is held up against the band 6 by the pipe P. The gripping action of this jaw 8 tends to make possible the employment of thinner metal for the band 6. The bolt 2 is then screwed down to clamp the connector firmly to the pipe P. The kink 10 provides the initial resistance 100 against separation of the band 6 from the head H but as the connector tightens the gripping jaws 8 and 9 bite into the band 6 to reinforce the hold of the kink 10, the pipe forcing the band 6 against the jaw 9 and the jaw 8 against the band, opposite 105 faces of the band thus being gripped. These gripping jaws described may be termed 110 re-

finements of the invention because they merely increase the gripping action between the band 6 and the head H. The relative positioning of the said parts, with the band 6 woven through the head as illustrated, alone insures a secure connection.

What is claimed and what is desired to be secured by United States Letters Patent is:—

- 10 1. An electrical ground connector consisting of a sheet metal body portion; a coöperating flexible thin metal band and a screw means for drawing the end of said band toward said body portion to effect good electrical connection between said parts and a ground pipe; said body portion having formed integrally therewith a terminal adapted to connect with a conductor and an enlarged pipe-engaging head having two laterally extending slots forming a central bar to overlie said band and being of a size to permit the weaving therethrough of said flexible metal band, said band being sufficiently thin and flexible to be drawn manually under said bar and over said head to take up all slack about the ground pipe and be gripped in any indeterminate part of its length as distinguished from being gripped in fixed spaced steps, the slot first entered by said band having the metal along its edge facing said bar formed into an upwardly biting jaw to bite into the under face of said band.
- 15 3. In an electrical ground connector comprising a thin metal band to extend about a ground pipe; and a second part having a bolt hole; a bolt adapted to pass through said hole for the purpose of drawing up the free end of said band; a nut having the free end of said band wrapped completely about said nut; the wrappings of said free end having perforations alined with but larger than the hole in the nut so that the stress from the pull of the bolt upon the nut can be transmitted to the band from a full side face of the nut against the band and so that said nut is held by the band against turning, for the purpose of improving the quality of both electrical and mechanical connection between the parts and to permit minimum thinness for the band.
- 20 2. An electrical ground connector consisting of a sheet metal body portion; a coöperating flexible thin metal band and a screw means for drawing the end of said band toward said body portion to effect good electrical connection between said parts and a ground pipe; said body portion having formed integrally therewith a terminal adapted to connect with a conductor and an enlarged pipe-engaging head having two laterally extending slots forming a central bar to overlie said band and being of a size to permit the weaving therethrough of said flexible metal band, said band being sufficiently thin and flexible to be drawn manually under said bar and over said head to take up all slack about the ground pipe and be gripped in any indeterminate part of its length as distinguished from being gripped in fixed spaced steps, the slot first entered by said band having the metal along its edge facing said bar formed into an upwardly biting jaw to bite into the under face of said band.
